United States Patent Office

Des. 206,068
Patented Oct. 25, 1966

206,068

KEYBOARD

Charles F. Grossman, Sunnyvale, Calif., assignor to Am-
pex Corporation, Redwood City, Calif., a corporation
of California

Filed June 21, 1965, Ser. No. 85,813

Term of patent 14 years

(Cl. D26—5)

FIG. 1

FIG. 2

FIG. 1 is a perspective view of a keyboard, showing the top, front, and right side of my new design;

FIG. 2 is a left-side elevational view thereof; and

FIGURE 3 is a rear elevational view thereof.

The dominant features of my new design are shown in solid lines in the drawing.

I claim:

The ornamental design for a keyboard, substantially as shown and described.
